UNITED STATES PATENT OFFICE.

CHARLES DAHMEN, OF CLOSTER, NEW JERSEY, ASSIGNOR TO SIMON ZINN, INC., OF NEW YORK, N. Y., A CORPORATION OF NEW YORK.

HAND-BAG FRAME, TOILET ARTICLE, AND VANITY CASE.

1,404,379.

Specification of Letters Patent. Patented Jan. 24, 1922.

Application filed October 29, 1920. Serial No. 420,346.

To all whom it may concern:

Be it known that I, CHARLES DAHMEN, a citizen of the United States, residing at Closter, county of Bergen, and State of New Jersey, have invented a new and useful Improvement in Hand-Bag Frames, Toilet Articles, and Vanity Cases, of which the following is a specification.

This invention relates to improvements in handbag frames, toilet articles and vanity cases. The ordinary handbag frame functions as a frame for supporting the flexible sack, cloth or mesh, and as a closure for the top of the sack.

15 An object of my invention is to build into a handbag frame a suitable number of compartments for carrying small articles, as tickets, change and toilet articles. These compartments may be provided with suitable 20 covers.

Another object of my invention is to provide a handbag frame of the above type with a closure for all the compartments, which closure may readily carry a mirror 25 accessible when the compartments are opened.

Another object of my invention is to provide structures of the above type with such hinges and catch mechanism that all parts of the structure are permanently connected 30 together in a convenient manner to render the sack, compartments and mirror readily accessible.

In the accompanying drawings, I have shown by way of illustration several embodiments in which my invention may take 35 form. It is understood that the invention may be embodied in structures, having various other configurations within the scope of my invention.

40 In the drawings, Figure 1 is a top plan view of one form of a handbag frame, the closure for the compartment-covers being raised and parts broken away.

Fig. 2 is a section along the line 2—2 of 45 Fig. 1, the closure being lowered.

Fig. 3 is a sectional view along the line 3—3 of Fig. 1 with the closure in the same position.

Fig. 4 is an inverted plan view of a portion of the frame shown in Figs. 1 to 3, inclusive.

Fig. 5 is a top plan view of another form 55 of handbag frame, the closure for the compartment-covers being raised and parts broken away.

Fig. 6 is a section on the line 6—6 of Fig. 5, the closure being lowered.

Fig. 7 is a section on the line 7—7 of Fig. 5, with the closure lowered.

Fig. 8 is a top plan view of another form 60 of handbag frame, the closure for the compartment-covers being raised and parts broken away.

Fig. 9 is a section along the line 9—9 of Fig. 8, with the closure lowered.

Fig. 10 is a section along the line 10—10 of Fig. 8, with the closure lowered.

Fig. 11 is a top plan view of another form 70 of handbag frame, the closure for the compartment-covers being raised.

Fig. 12 is a section along the line 12—12 of Fig. 11, the closure being lowered.

Fig. 13 is a section along the line 13—13 of Fig. 11, parts being broken away and the closure lowered.

Fig. 14 shows a modified form of catch mechanism.

Fig. 15 shows the connecting of the ends 80 of a rolled main frame by means of a part of a hinge.

Referring to the structure shown in Figs. 1 to 4, inclusive, the main frame 20 is in the form of an annular ring. As shown in Figs. 2 and 3, the cross section of an element of this ring is substantially an inverted U, the longer and outer side 21 of which is provided with a plurality of holes 22 for fastening the frame to the cloth or mesh of the sack. One side of the frame carries a hinge pin 23, while the opposite side of the frame carries one part 24 of a catch mechanism. This part may be a long spring fastened at 25 to the inner and shorter side of the U. It is provided at the free end with an aperture 26 and with a button 27 which projects outwardly through an aperture 28 in the frame. When the frame is fastened to the sack in the manner described, access to the interior of the same may be had through the annular main frame 20.

100 A cover-member 29 has the same configuration as the outside of the main frame 20 except where it is cut away to provide space for one member 47 of a hinge which fastens it to the main frame. The cover-member 29 carries one co-operative element 30 of a catch mechanism, which element is adapted to pass downwardly through an aperture 31 in the top of the main frame into the aperture 26 in the member 24.

The cover-member acts as a closure for the top of the bag-frame, and is itself compartmented, i. e., provided with one or more compartments. In the frame illustrated, 5 two compartments are provided by depressing the central portion of the cover-member to form a recess 32 having an annular wall 33 and placing a transverse partition 34 across the recess. A long hinge pin 35 is 10 placed directly above the partition 34, the ends of the pin passing through apertures 36 in the side walls of the recess. Compartment-covers 37 and 38 are hingedly carried on the pin 35, each of them being 15 adapted to close one or the other of the compartments 39 and 40. Suitable stops 41 are provided about the recess wall 32 to limit the closing movement of these compartment-covers. Spring catches 42, each 20 having a projecting tongue 43, are provided, one for each compartment and to hold it in closed position. A coiled spring 44 is also wound about the hinge pin 35, one end 45 of the spring 44 being under the cover 37 and the other end 46 under the cover 38.

Intermediate the hinge member 47 on the cover-member, and the near side of the recess 32, a hinge pin 48 is mounted, and a closure 49 is hinged on this hinge pin. This closure 30 is large enough to cover the compartments 39 and 40 and their co-operating covers and catch mechanism. It is provided, on the side opposite the hinge pin 48, with a pin 50 which is adapted to pass through an 35 aperture 51 in the top of the cover-member and to co-operate with a catch member 52 supported on the end of a spring 53 attached at 54 to the cover-member. A button 55 is connected to operate the catch member 52. 40 The closure 49 is thrown to open position by means of a spring 56 wound about the pin 48. A mirror 57 is supported inside the closure member by means of projections 58. The handbag may be carried by a handle 45 such as a chain 59 connected to eyes 60 on the cover.

Manipulation of the button 55 releases the closure 49 permitting it to go into the position indicated in Fig. 1. The mirror is then 50 available and by pressing one of the spring catches 42, the corresponding compartment-cover is thrown open by the spring 44 to permit access to the compartment underneath the cover. Manipulation of the button 55 55 releases the cover-member 29 which can be thrown back on the hinge pin 23 to permit access to the interior of the handbag.

The device shown in Figs. 5 to 7, inclusive, is similar to that already described, and 60 corresponding parts are assigned in these figures the same reference characters with the letter *a* added. The differences in these structures reside in the following: Here the compartment-covers 37' and 38' 65 are not biased to open position by a spring

nor held closed by a spring catch. The periphery of either cover is adapted to frictionally engage a side wall of the recess. To operate this releasable interconnection, finger pieces 370 and 380 are provided. A 70 spring catch 61 having a finger piece 62 is adapted to engage the closure 49^a. The chain 59^a is fastened to eyes 60^a carried by the cover member 29^a.

The device shown in Figs. 8, 9 and 10 is 75 similar to those heretofore described and corresponding parts are assigned in these figures the same reference characters with the letter *b* added. The main frame 20^b is rectangular and the cover-member is connected to it by two hinge mechanisms 23^b and 47^b. The cover-member is divided into four compartments 63, 64, 65 and 66 having individual compartment-covers 63', 64', 65' and 66', which are all covered by the closure 80 85 49^b hinged to the cover-member.

The device shown in Figs. 11, 12 and 13 is somewhat similar to those heretofore described, the corresponding parts being assigned in these figures the same reference 90 characters with the letter *c* added. The compartment-cover member 29^c in this case is provided with open receptacles such as those designated 67 and 68, which may be stamped therein. A mirror 57^c, carried on the closure 95 49^c, is adapted to close the top of these receptacles. The compartment-cover member 29^c is hinged to the main frame by hinge mechanism 69, while the closure 49^c is hinged to the cover by hinge mechanism 100 70. A spring catch 71 carried on closure 49^c releasably interengages a projection 71 on the cover-member 29^c, while another spring catch 73 releasably engages an abutment 74 on the main frame 20^c. Access to 105 the handbag may be had by releasing the latter spring catch while access to the compartments may be had by releasing both of these catches. A lip stick or pencil may be held in position by means of the spring 110 clip 75.

Another form of catch mechanism is shown in Fig. 14. The cover-member is there shown at 80 and the main frame at 81 which, as before, may be of channel or 115 U shaped cross section with one side 82 longer than the other side 83. A sliding bolt 84, carried inside the channel on a pin 85, is connected to an abutment 86 accessible outside the frame, a slot 87 being provided 120 to limit the motion. A tang 88 is struck from the inner side 83 of the channel and a coiled spring 88' confined between the bolt and this tang. The bolt has an element 89 to cooperate with an element 90 125 carried on the cover 80.

The main frames 20, 20^a, 20^b, 20^c may be made in various ways. One method would be by punching them from sheet material, but this is not well adapted for use where 130

it is desired to have a bag frame with a filigree design. In this case it is preferable to take a piece of channel stock and bend it to the proper shape bringing the ends 5 of the channel stock together. A mode of fastening these ends together is shown in Fig. 15 wherein the ends 91 and 92 are butted close together and fastened to one part 93 of the hinge by means of ears 94 10 integral with the hinge member, which ears pass through apertures 95.

While I have described in considerable detail several embodiments in which my invention may take form, I desire it to be 15 understood that the invention may be embodied in other forms than those specifically described, also that certain parts may be omitted, thereby providing a hand-bag frame which has certain of the properties 20 of the completed structures shown.

What I claim is:

1. A frame for hand-bags or the like, comprising a main frame having a depending peripheral portion for attachment to 25 the sack, a comparted cover-member hingedly carried by the main frame, catch mechanism releasably interconnecting the cover-member and the main frame, a compartment-cover carried by the cover-member 30 and a closure over the compartment-cover.

2. A frame for hand-bags or the like, comprising a main frame, a comparted cover-member carried by the main frame, a compartment-cover carried by the cover-member, 35 and a closure over the compartment-cover.

3. A frame for hand-bags or the like, comprising a main frame, a comparted cover-member hingedly carried by the main frame, catch mechanism releasably interconnecting 40 the cover-member and the main frame, a compartment-cover carried by the cover-member and a closure over the compartment-cover.

4. A frame for hand-bags or the like, comprising a main frame having a depending peripheral portion for attachment to 45 the sack, a comparted cover-member carried by the main frame, a compartment-cover carried by the cover-member and a closure over the compartment-cover.

5. A frame for hand-bags or the like, comprising a main frame having a depending peripheral portion for attachment to 55 the sack, a comparted cover-member hingedly carried by the main frame, catch mechanism releasably interconnecting the cover-member and the main frame, a compartment-cover carried by the cover-member, a closure over the compartment-cover and a 60 mirror carried inside the closure.

6. A frame for hand-bags or the like, comprising a main frame, a comparted cover-member carried by the main frame, a compartment-cover hingedly carried by the 65 cover-member, a releasable interconnection

between the compartment-cover and cover-member and opposite the hinge and a closure over the compartment-cover.

7. A frame for hand-bags or the like, comprising a main frame, a comparted cover-member hingedly carried by the main frame, catch mechanism releasably interconnecting the cover-member and the main frame, a compartment-cover hingedly carried by the cover-member, a releasable interconnection 75 between the compartment-cover and cover-member and opposite the hinge and a closure over the compartment-cover.

8. A frame for hand-bags or the like, comprising a main frame having a depending 80 peripheral portion for attachment to the sack, a comparted cover-member hingedly carried by the main frame, catch mechanism releasably interconnecting the cover-member and the main frame, a compartment-cover 85 hingedly carried by the cover-member, a releasable interconnection between the compartment-cover and cover-member and opposite the hinge, a closure over the compartment-cover and a mirror carried inside the 90 closure.

9. In a toilet article, in combination, a sheet metal member having an outer peripheral portion, a central portion depressed relative to the outer portion, a transverse wall 95 dividing the depression into compartments, a hinge pin above the wall and a cover for each compartment each cover being mounted on the hinge pin.

10. A cover-member for the main frame 100 of hand-bag frames, comprising a sheet metal member having an outer peripheral portion, a central portion depressed relative to the outer portion, a transverse wall dividing the depression into compartments, a 105 hinge pin above the wall, a cover for each compartment each cover being mounted on the hinge pin, the outer peripheral portion of said cover-member being provided with hinge and catch mechanism for releasably 110 and hingedly fastening it to the main frame.

11. A cover-member for the main frame of hand-bag frames, comprising a sheet metal member having an outer peripheral portion, a central portion depressed relative to the 115 outer portion, a transverse wall dividing the depression into compartments, a hinge pin above the wall, a cover for each compartment each cover being mounted on the hinge pin, the outer peripheral portion of said 120 cover-member being provided with hinge and catch mechanism for releasably and hingedly fastening it to the main frame, and further provided with hinge and catch mechanism for releasably and hingedly fastening a closure over the compartment cov- 125 ers.

12. In a toilet article, in combination, a sheet metal member having an outer peripheral portion, a central portion depressed rel- 130

ative to the outer portion, a transverse wall dividing the depression into compartments, a hinge pin above the wall, a cover for each compartment each cover being mounted on the hinge pin and a closure hinged to the peripheral portion of the sheet metal member for covering the compartment-covers.

13. A main frame for hand-bags or the like, wherein the ends of a channel or U-shaped member are in end-to-end abutting relation to form a closed figure with one side wall of the channel or U-shaped member constituting the outer periphery thereof and the other side wall constituting the inner periphery thereof, are combined with a hinge

member extending across the joint between said ends and fastened to the outer peripheral wall adjacent said ends.

14. A frame for handbags or the like, wherein the ends of a sheet metal member comprising elements at substantially right angles to one another are in end-to-end relation to form a closed figure with one of said elements constituting the outer periphery of the figure and the other constituting the top of the frame, and wherein a hinge member extends across the joint between the ends of the first mentioned element and is fastened to said ends, bridging the joint therebetween.

CHARLES DAHMEN.
